THEODORE T. POMEROY, OF HAVERHILL, MASSACHUSETTS, ASSIGNOR TO SAFETY GAS LIGHTER CO., OF HAVERHILL, MASSACHUSETTS, A CORPORATION OF MASSACHUSETTS.

PYROPHORIC RENEWAL FOR GAS-LIGHTERS.

1,212,156.

Specification of Letters Patent.

Patented Jan. 9, 1917.

Application filed June 1, 1915. Serial No. 31,341.

To all whom it may concern:

Be it known that I, THEODORE T. POMEROY, a citizen of the United States, residing at Haverhill, in the county of Essex and State of Massachusetts, have invented an Improvement in Pyrophoric Renewals for Gas-Igniters, of which the following is a specification.

This invention particularly relates to certain improvements in the spark-producing elements of pyrophoric gas-igniters, or to that part of the igniter which is moved in contact with the abrading member, and is adapted to be renewed.

In that class of igniters of the so-called "tongs" type, it has been customary to provide a brass nipple, one end of which is screw-threaded to receive the end of one of the igniter arms, and has the pyrophoric alloy inserted in the opposite end thereof, so that a substantial portion of said alloy projects beyond the end of the nipple. This means of holding the alloy has various objections;—the alloy is brittle, and relatively large chips are likely to be broken from the projecting-portion when abraded to produce the sparks, so that the alloy is thus wasted. It also frequently happens that the alloy is not held with sufficient security and is dislodged from the nipple. Only the portion of the alloy which projects beyond the nipple can be used, for, when the alloy becomes worn down to the end of the nipple, the latter prevents wear beyond this point, or prevents the alloy from being abraded to a sufficient extent to produce a satisfactory quantity of sparks. The result is that practically all of that portion of the alloy, which is inserted in the nipple, is not used, the loss frequently being fully 25%. As the alloy is very expensive, as compared with other metals, the waste which occurs through this method of holding the alloy amounts to a large sum, when the large number of these devices, which are used, are considered.

A primary object of my invention is to provide means for holding the pyrophoric alloy in a gas-igniter of the type above referred to, so that it will not be dislodged, chipped, or broken by the file, and so that practically all of the alloy may be used. In a general way, I accomplish this object by providing a sleeve, in which the pyrophoric alloy may be inserted throughout its entire length, so that no portion thereof will pro-

ject beyond the end of the sleeve, and by forming the sides of said sleeve of a metal which may be cut away with a file more easily than the alloy, so that the file will not be prevented from having easy access to the alloy.

I have ascertained, by experiment, that merely to employ, as an alloy holder, a metal which may be cut away with a file more easily or readily than the alloy, will not necessarily accomplish the desired result, and the metal used must, primarily, be of a frictional nature rather than anti-frictional. For example;—such metals as copper, lead, and aluminum, which are of anti-frictional nature, reduce the frictional resistance of the file, when used in the relation above referred to, so that the heat generated is lessened, and the quantity or volume of the sparks produced is decreased, the sparking action being practically deadened. Such metals also tend to fill the teeth of the file, so that its abrading action is greatly lessened. On the other hand, many metals which are of frictional nature are so hard that they may only be filed with difficulty. That is, if iron, for example, were used in the above described relation, the iron would not be filed away as readily as the alloy, and the formation of suitable sparks would be prevented, while the dulling effect on the file would also be great.

A more specific object of my invention, therefore, is to provide a form of alloy holder with which the metal of the holder, besides resisting abrasion to practically no greater an extent than the alloy, will also possess strong frictional qualities, so that the amount of heat generated and the heat and igniting power of the sparks, and, at the same time, the luminosity of the sparks, will also be increased. I accomplish this object by forming a containing cup for the pyrophoric alloy from a metal which not only may be abraded more easily or readily than the alloy, and which has a much less dulling effect on the file than the alloy, but which is of such a character that, while the particles thereof removed by the file will not become ignited by the filing action alone, they will be ignited by the ignition of the particles of alloy, so that the temperature, volume, and luminosity of the sparks emitted will be increased. The metal which, in so far as I have been able to discover, possesses all of

the above characteristics and capabilities, to the most satisfactory degree, is magnesium.

For a more complete disclosure of my invention, reference is made to the following specification in connection with the accompanying drawing, in which:—

Figure 1 is a side elevation of an igniter of the tongs type. Fig. 2 is a bottom plan view thereof. Fig. 3 is an enlarged detail sectional view of the alloy holder. Fig. 4 is a side elevation, partly in section of a renewal device, made according to my invention, and, Fig. 5 is a plan view thereof.

In the drawing *a* indicates a pyrophoric igniter of the well-known tongs type, one of the arms of which bears a transversely disposed file *b*, and the other arm of which has an upturned end on which a sleeve *c* is mounted, said sleeve having a coupling-ring *d* threaded thereon.

According to my invention, I form a cylindrical cup *e* of the metal magnesium, said cup being provided with an annular flange *e'* at its base, and having cylindrical side walls, the external diameter of said walls being slightly less than the internal diameter of the coupling-ring *d*, so that said cup may be readily inserted in the coupling-ring *d*, and clamped against the end of the sleeve *c* by the engagement of said ring with said flange *e'*. A cylindrical piece of cerium-iron alloy *f* is tightly fitted in the cup *e*, with its inner end resting against the bottom of the cup, and its outer end flush with the rim thereof.

In use, the end of the piece of alloy, and the rim of the cup bear against the file, and, as the file and alloy are moved relatively, the file will abrade the alloy and produce sparks, and at the same time, the file will cut away the sides of the cup, so that the surface of the alloy and the rim of the cup will continue to be flush, and as magnesium, the metal of which the cup is formed, may be cut away with a file more readily and easily than the alloy, it will be obvious that the metal of the holder will not prevent engagement of the file with the alloy to a substantial extent, so as to interfere with the sparking operation, and the dulling effect on the file will not be increased. There is, however, a somewhat increased frictional effect over that which would take place if the alloy extended beyond the cup walls, and the increased heat thereby caused, tends to cause a more complete ignition of the cerium-iron particles which are thrown off by the abrasive action of the file. As more sparks are thus likely to be produced the efficiency of the igniter is thereby increased, as the ignition of the gas is more likely to take place, under ordinary conditions. The particles of magnesium, which will also be thrown off by the file, ignite at a somewhat higher temperature than the cerium-iron

particles, and alone, will not ignite in air by ordinary abrasion, but, as these particles are thrown off simultaneously with the cerium-iron particles, they will become mixed therewith and the particles of cerium-iron, when ignited, will, in turn, ignite the particles of magnesium, thereby increasing both the heat and luminosity of the sparks produced, magnesium burning, as it does, with a very white flame. This increased illuminating effect is of advantage when the igniter is used in the dark, and it is, for example, desired to locate a gas jet.

The magnesium cup, by completely surrounding the alloy, holds it securely in place so that it is unlikely to be displaced and prevents the latter from becoming chipped off and wasted. This arrangement, moreover, causes the alloy to be retained until it is completely filed away, the cup being held so that its bottom is above the level of the ring *d*, thereby permitting all of the alloy contained therein to be used. As a result, the extent to which a piece of alloy, of the size which it is practicable to employ in this connection, may be used, is greatly increased, this saving being due in part to the fact that all the alloy is used and large particles are not chipped off and wasted. The rapidity with which the alloy is cut away is also reduced or retarded by the magnesium cup which contains it, on account of the increased surface which is filed. At the same time, the efficiency of the igniter is increased, without increasing the amount of alloy employed. That is, the igniting effect is substantially as great as if a piece of alloy were employed which had a diameter equal to the combined diameter of the alloy and holder, while the luminosity of the sparks produced will be increased, and, as magnesium is a much less expensive metal than the alloy, a substantial saving is made in the amount of alloy necessary to produce the desired results. It will be understood that the part which is renewed, and is sold as a commercial article as a "renewal" is the magnesium cup having the alloy inserted therein.

I claim:—

1. A friction gas-igniter, comprising co-operating, abrading and pyrophoric elements, said pyrophoric element comprising two metals arranged side by side in close contact, to provide a continuous abrader-engaging face, and means to move the abrading element over said face, to cause simultaneous abrasion of said metals, the igniting point of the particles from one of said metals being relatively low as compared with that of the other, and the latter having frictional qualities, so that the heat generated from the abrasion thereof, tends to cause ignition of the particles from the former.

2. A friction gas-igniter, comprising co-

operating, abrading and pyrophoric elements, said pyrophoric element comprising a piece of the metal cerium and a piece of a metal having relatively high frictional qualities as compared with those of the cerium, said metals being arranged side by side in close contact, to provide a continuous, abrader-engaging face, and means to move the abrading element over said face, 10 to cause simultaneous abrasion of said metals.

3. A friction gas-igniter, comprising co-operating, abrading and pyrophoric elements, said pyrophoric element comprising 15 two pieces of metal, one the metal cerium, and the other the metal magnesium, arranged side by side in close contact, to provide a continuous abrader-engaging face, and means to move the abrading element 20 over said face to cause simultaneous abrasion of said metals.

4. A renewal device for a pyrophoric igniter, comprising a cup formed of a metal having high frictional qualities, and a piece 25 of pyrophoric alloy closely fitted in said cup, with its outer end flush with the rim

thereof, the file resisting qualities of the metal of the cup being less than those of the alloy.

5. As an article of manufacture, a renewal 30 device for a pyrophoric igniter, comprising a magnesium metal cup having a pyrophoric alloy inserted therein with its outer end flush with the rim of the cup.

6. An igniter having a coöperating, abrad- 35 ing and pyrophoric element, said pyrophoric element comprising a cup formed of magnesium metal and having a piece of pyrophoric alloy tightly fitted therein against the bottom thereof, and with its outer end 40 flush with the edges of the side walls of the cup and means to hold the cup in position to be abraded across its rim and the exposed end of the alloy to remove the side walls and the alloy by abrasion, simulta- 45 neously.

In testimony whereof, I have signed my name to this specification.

THEODORE T. POMEROY.
